BROODER

Arthur R. Wood, Santa Cruz, Calif., assignor to
Wood Brothers Co., Santa Cruz, Calif., a cor-
poration of California

Application March 28, 1932. Serial No. 601,614

5 Claims. (Cl. 119—32)

This invention relates to brooders of the type employed in chicken hatcheries for housing and warming newly hatched chicks, and especially to a gas heated brooder in which the heat is applied to the chicks in the form of radiant energy.

The object of the present invention is to generally improve and simplify the construction and operation of gas heated brooders; to provide a gas heated brooder in which the heat is applied to the chicks in the form of radiant energy; to provide a brooder in which radiant heat is uniformly directed over the entire floor area covered by the hover of the brooder; to provide a brooder structure which permits a free discharge of the products of combustion resulting from the burning of the gas so as to prevent contamination of the air within the brooder; and further, to provide a brooder structure in which the burners induce a continuous flow of fresh air, said air entering the bottom or open end of the brooder so as to continuously renew and maintain fresh air within the brooder and at the same time maintain an ample supply for the burners.

The brooder is shown by way of illustration in the accompanying drawings, in which—

Fig. 1 is a side elevation of the brooder partially in section.

Fig. 2 is an enlarged bottom view of the inner cone-shaped head of the brooder, together with the burners and the radiant element supported thereby.

Fig. 3 is an enlarged section and side elevation similar to Fig. 1 taken on line III—III of Fig. 2.

Fig. 4 is an enlarged central vertical section of the manifold whereby gas is delivered to the main burners and also to the pilot burners said section being taken on line IV—IV Fig. 2.

Referring to the drawings in detail and particularly Figs. 1 and 2, A indicates the hover of a brooder, which, in this instance, is supported by leg members, such as indicated at 2. The lower end of the hover is open and is maintained a fixed distance above a floor or other support provided so as to permit the chicks to freely enter whenever desired. The hover may be of any shape desired, preferably octagon or cone-shaped as here shown; the hover being frustoconical and being closed at the upper end by a head plate 3.

Secured to the lower side of the head plate is a cone-shaped inner plate 4. This plate forms an interior chamber 5, which will hereinafter be referred to as a flue chamber, as it receives the products of combustion discharging from the burners and it is also connected with a discharge

flue or stack 6 or the like to carry the fumes away. Suitably secured to the bottom portion of the inner cone-shaped head member 4 are a plurality of gas burners, such as indicated at 7. These burners are of standard construction and they are identical, hence the description of one will suffice.

The inner end of each burner is Venturi-shaped, as indicated at 8, see Fig. 4, and it is provided with air inlet openings 9 and a rotary shutter 10, whereby the amount of air admitted may be regulated. A central hub member 11 is provided to secure the burner with relation to the manifold, as indicated at 12, and also to receive a nozzle 13. The burner is otherwise extended to form a tube, shown at 7 in Fig. 3, and it terminates in a head member 14 in which are formed a plurality of perforations 15 through which the gas and air mixture discharges.

That is, each burner is of the Bunsen type. 75 The gas discharged by the nozzles 13 enters the Venturi end of the tube 7 and thereby induces a flow of air through the openings 9, the amount of air admitted being regulated by the shutters 10. The mixture formed discharges through the 80 perforations 15 and the flame, when ignited, discharges against a series of glow elements indicated at B. The manifold employed is in the form of a cross as there are four burners. The manifold is extended upwardly through the flue 85 chamber in the form of a tube, as shown at 16, and this is connected through means of an elbow 17 and a nipple 18 with a valve 19, the valve being connected with a supply pipe 20 and the flow of gas being regulated by the valve 19. This may 90 be controlled by a thermostat so as to maintain a uniform temperature, but as a thermostat control is old a manually controlled valve is disclosed. Each burner is supplied with a pilot burning tube 21, which terminates adjacent the 95 discharge openings 15 of the burners a small flame being continuously projected in front of the openings 15 so as to ignite the gas when the main burners are turned on.

The pilot tubes 21 connect with an extension 100 22 on the gas manifold, this extension being separated from the manifold proper by a partition member 23. A supply tube 24 connects with the main supply line 20. The gas enters the tubular extension 16 of the manifold, as shown, 105 it passes through the partition 23 into the extension chamber 22, the flow of gas from this tube being regulated by a set screw 25 so that any size pilot flame desired may be continuously maintained.

The glow elements may be of any shape desired. In this instance, they are shown as rectangular shaped plates with side flanges 30 formed on opposite sides thereof. The glow elements may be made of any suitable refractory or like material and the surface between the side flanges is provided with projecting pins or tips 31, which will assume a glowing incandescent temperature when the flame of the main burners 10 is directed against the same. In fact, the flame from the burners discharges against the refractory glow elements, passes over the surface of the same and into hood-shaped members, such as indicated at 40. These hoods are connected 15 through openings 41 with the flue chamber and all products of combustion will thus escape through the hoods into the flue chamber and will pass from the flue chamber into the stack 6 and out into the open atmosphere, hence preventing contamination of the atmosphere in under the hover A.

The glow elements are angularly disposed, as shown, and as such will project heat and light rays in the form of radiant energy downwardly 20 against the floor or other support covered by the hover. The radiant energy thus directed will be uniformly distributed and a uniform temperature will be maintained over the entire floor area. The products of combustion from the main burners, as previously described, will escape through 25 the hoods 40 into the flue chamber and from there into the stack. This continuous flow of heated gases will naturally induce a continuous flow of fresh air. This air enters through the 30 annular opening formed between the bottom of the hover and the floor. This annular opening is enormously large in area when compared with the discharge outlets 41, which form communication between the hoods and the flue chamber, 35 and, as such, avoids any draft. That is, the fresh air entering around the lower edge of the hover will have such a low velocity that cooling of the chicks on the outer fringe will be prevented. The flow of air is, however, more than sufficient to 40 supply the burners and at the same time maintain a fresh clean atmosphere under the hover.

While certain features of the present invention are more or less specifically described, I wish it understood that various changes may be resorted 50 to within the scope of the appended claims. Similarly, that the materials and finish of the several parts employed may be such as the manufacturer may decide, or varying conditions or uses may demand.

Having thus described my invention, what I claim and desire to secure by Letters Patent is—

1. A brooder comprising a substantially cone-shaped hover open at its lower end and closed by a head member at the upper end, an interior head member secured thereto and forming a flue chamber, a stack connected with the flue chamber, a

plurality of gas burners supported by the inner head and adapted to direct flame against the exterior surface thereof, a plurality of radiant elements interposed between the inner head and the flames so as to be raised to a glowing temperature by the flames and so positioned as to direct radiant energy downwardly against the surface covered by the hover, and a plurality of hood members one adjacent an end of each of said radiant elements supported by the inner head and adapted to direct the products of combustion into the flue chamber.

2. A brooder comprising a substantially cone-shaped hover open at its lower end and closed by a head member at the upper end, a cone-shaped inner head secured to the first named head, the space between said heads forming a flue chamber, a stack connected with said chamber, a plurality of gas burners supported at the lower end of the cone-shaped head and adapted to direct flames on lines substantially parallel with the cone-shaped head, glow elements carried by the cone-shaped head and interposed between the head and the flames projected by the burners, and a hood member adjacent each glow element to trap and direct the products of combustion produced by the flames into the flue chamber.

3. A brooder comprising a substantially cone-shaped hover, an inverted frusto conical plate within the hover and forming a flue chamber therein, a fuel manifold extending centrally and vertically through said flue chamber, burners extending radially from the lower end of said manifold and adapted to direct flames along the surface of the conical face of said plate, a heat radiating element in the path of each of said flames, said plate having an opening and a hood member adjacent the end of each radiating element to direct the products of combustion into said flue chamber.

4. A brooder comprising a hover having a flue chamber in the upper central part thereof, a fuel manifold extending vertically through said chamber, burners extending radially of the hover, said fuel manifold having a closed chamber at its lower end, a fuel supply conduit within the manifold and communicating with said chamber, and pilot tubes leading from said chamber, one to each of said burners.

5. A brooder comprising a hover having a flue chamber in the upper central part thereof, a fuel manifold extending vertically through said chamber, burners extending radially of the hover, said fuel manifold having a closed chamber at its lower end, a fuel supply conduit within the manifold and communicating with said chamber, pilot tubes leading from said chamber, one to each of said burners, and a screw threaded through the chamber wall co-axial with the end of said supply tube to adjust the flow of fuel to said pilot tubes.

ARTHUR R. WOOD.
